(57) **CLAIM**

The ornamental design for a hedge trimmer, as shown and described.

DESCRIPTION

FIG. 1 is a perspective view of top, front, and left side of a hedge trimmer showing my new design;

FIG. 2 is a left side view thereof;

FIG. 3 is a right side view thereof;

FIG. 4 is a top plan view thereof;

FIG. 5 is a bottom view thereof;

FIG. 6 is a rear view thereof;

FIG. 7 is a front view thereof;

FIG. 8 is a perspective view of top, rear, and right side thereof; and,

FIG. 9 is a perspective view of FIG. 1 with detachable battery. The broken line showing of the hedge trimmer is included for the purpose of showing portions of the article and forms no part of the claimed design.
